UNITED STATES PATENT OFFICE

EDDY A. K. STANGER, OF COLUMBUS, OHIO

SANITARY CIGARETTE ROLLING DEVICE

Application filed November 3, 1931. Serial No. 572,868.

This invention relates to cigarette rolling devices and has for its object to provide a simple and effective device into which tobacco may be deposited and rolled to cylindrical form and subsequently ejected from the device into the wrapper of the cigarette which has previously been rolled into the proper tubular form.

A still further object of the invention is to provide in a device of the character above mentioned means for retaining one end of the cigarette wrapper in alignment with the discharge end of the device to insure proper feeding, and to facilitate such feeding from the device to the wrapper.

These and other objects are obtained by the construction described in detail in the following specification and clearly illustrated in the accompanying drawings wherein:

Figure 1 is a top plan view of the device, the parts being shown in position subsequent to receiving a charge of tobacco.

Figure 2 is a side elevational view of the device.

Figure 3 is a longitudinal sectional elevational view therethrough, clearly showing the manner of holding one end of the wrapper in alignment with the discharge end of the device.

Figure 4 is a transverse sectional view taken substantially on the line 4—4 of Figure 2.

Figure 5 is a fragmentary top plan view of one end portion of the trough part of the device.

With reference more in detail to the drawings it will be seen that I provide a trough 5 that is preferably formed from a tube, and provided with a slot 6 elongated longitudinally to provide a mouth or entrance opening for the trough. The ends of the trough are closed by caps 7, 8, each of which on one side is provided with an annular groove 9 accommodating a proximate end of the trough 5.

Adjacent each end thereof the trough 5 is provided with an exterior annular groove 10 within which is a ring 11 preferably formed of spring wire, and serving to key a cap to the end of the trough, each cap be-

ing provided with an internal circular groove 12 for registry with a groove 10 and receiving a portion of the key ring 11. The rings 11 serve to retain the knobs 7 and 8 on the ends of the trough 5 against axial displacement, but permit of relative rotation of the trough and the knobs 7 and 8.

A cigarette rolling apron 13 in the form of a piece of fabric or other suitable material, preferably spring metal, of suitable dimensions, being preferably of elongated rectangular shape, is adjacent one longitudinal edge thereof, rolled or wrapped into fixed engagement about a rod 14, the same being adapted for arrangement within the trough 5 and having its end secured in sockets 15 provided in the caps or knobs 7 and 8.

At a relatively opposite longitudinal edge thereof the apron 13 is likewise engaged with a second rod 16 the ends of which are engageable with proximate ends of the trough 5 and serve to retain this end of the apron 13 exteriorly of the trough, the apron extending through the slot 6 as is clearly shown. At this last mentioned edge the apron 13 is also provided with a flange or finger hold 17.

One of the knobs or caps for example the cap 8 is provided with an axial opening 18 through which is slidably an ejector rod 19 for ejecting the packed charge of tobacco through an axial outlet opening 20 provided in the other of the caps or knobs, for example the cap or knob 7.

At its outer side the cap or knob 7 is provided with an axial cylindrical projection 21 which at its outer end is beveled and provides a scoop like discharge mouth for the opening 20. The mouth 21 in actual practice is insertable in one end of the cigarette wrapper 22 when the latter has been rolled into proper tubular form as suggested in Figure 3.

In actual practice the apron 13 is in an unwound condition, the major portion thereof projecting from the trough 5 through the slot 6 of the trough. Preferably, the inner portion of the apron is permitted to sag or extend inwardly so as to form a trough like portion into which is placed the tobacco. Next, the cap forming knobs 7, 8 which have

their peripheries knurled or otherwise roughened are rotated relative to the trough 5 either by moving the knobs over a flat surface as for example a table or by rotating the knobs 5 or caps 7 and 8 by grasping each between the thumb and forefinger of each hand.

In this manner, the apron 13 is wound upon itself in the form of a roll about the tobacco as suggested in Figure 4. The pressure applied to the tobacco by rolling the apron 13 will tend to force the tobacco toward the ends of the device and will serve to compress the tobacco evenly throughout the length of the apron.

15 The cigarette is rolled until the ends of the rod 16 engage the end portions of the trough 5.

One end of a tube forming the wrapper of the cigarette and which is in the nature of a usual cigarette paper rolled in the form of a tube and having its ends sealed in a manner desired, is arranged to telescopically receive the mouth 21. The ejector rod 19 is then moved inwardly and through the 25 rolled apron 13 thus forcing the tobacco in its rolled and compressed form outwardly through the opening 20 and into the tube 23 for filling the same and completing the making of the cigarette. As is apparent when 30 the tobacco has been placed within the tube or wrapper 23, the latter may then be removed from its alining position with the discharge opening 20.

Even though I have herein shown and described the preferred embodiment of the invention, it is to be understood that the same is susceptible of changes, modifications and improvements coming within the scope of the appended claims.

40 Having thus described my invention, what I claim as new is:

1. In a cigarette rolling device, a trough like container, disk like members arranged at 45 relatively opposite ends of the container, means engaging said disk like members and proximate portions of said container for retaining said members against axial displacement but permitting said members to rotate relative to the container and a rolling apron 50 provided adjacent one edge thereof with means engaging said disk like members.

2. A cigarette rolling device comprising a substantially tubular container, a rolling apron, means for rolling the apron into a tube 55 elongated longitudinally of the container, and an ejector slidably longitudinally of the container for advancing the contents of the apron into a wrapper.

3. A cigarette rolling device comprising a 60 container open at its ends, rotatable caps closing said ends, a rod connecting said caps interiorly of the container, and a rolling apron secured at one end to said rod.

4. A cigarette rolling device comprising 65 a tubular container provided on one side with

an opening elongated longitudinally, a cap on each end of the container and provided with a circular groove receiving a proximate end of the container, inter-engaging means on the cap and on the proximate end of the container within the groove to retain the cap on said end of the container, a rolling apron, and means connecting the apron adjacent one end thereof with said caps.

5. A cigarette rolling device comprising a 70 trough, a cap rotatably mounted on each end of the trough and provided with a centrally located aperture, one of said caps having a tubular portion alining with the opening in said cap for telescopic reception within one end of a cigarette wrapper, a rolling apron, means connecting the apron at one end thereof of interiorly of the trough with said caps, and an ejector insertable into the trough through the opening in the other of said caps.

80 In testimony whereof I affix my signature.

EDDY A. K. STANGER.
